UNITED STATES PATENT OFFICE

123,103

DESIGN FOR A BOTTLE

Edward J. Murray, Willoughby, Ohio

Application April 1, 1940, Serial No. 91,404

Term of patent 7 years

To all whom it may concern:

Be it known that I, Edward J. Murray, a citizen of the United States, residing at Willoughby, in the county of Cuyahoga and State of Ohio, have invented a new, original, and ornamental Design for a Bottle, of which the following is a specification, reference being had to the accompanying drawing, forming part thereof.

Fig. 1 is an elevational view of a bottle showing my new design; Fig. 2 is a top plan view; and Fig. 3 is a sectional view on the line 3—3 of Fig. 1.

I claim:

The ornamental design for a bottle, substantially as shown.

EDWARD J. MURRAY.
